Inventor:

C. B. Wood

By Mumford & Co.

Charles B. Wood, of New York, N.Y.

Letters Patent No. 2200 Dated Oct. 10-1865.

Design for a Coach Lamp.

The schedule referred to in these Letters Patent and making part of the same.

To all whom it may concern:

Be it known that I, C. B. Wood, of the City, County, and State of New York, have invented a new and original design for a lamp for Wheel Vehicles, and do hereby declare that the following is a full, clear and exact description thereof, which will enable those skilled in the art to make and use the same, referring being had to the accompanying drawings, forming part of this specification.

The drawing represents a front elevation of the design.

This design for a lamp for wheel vehicles consists in having the body or main portion of the lamp constructed in the form of a series of planes A B B' the planes A being of diamond or lozenge shape and the planes B of tri-lateral form, the latter being between the upper and lower parts of the former, as clearly shown in the drawing.

The lower edges of the planes A, B' are connected to a base C, whose outline of which is a polygon and the upper edges of the planes are connected to a cap D, which may be described as a polygon having a convex or dish shape with the ventilator E attached centrally to it.

E is a tube for receiving the candle said tube depending from the centre of base C. Neither the tube E, nor ventilator E form any part of the design.

The planes A, B at the front and outer side of the body of the lamp are of glass, while those at the inner side and rear are of sheet metal. A horizontal central section of the body of the lamp is a polygon and a vertical central section

DFS. 2200

2 approximates to the same figure, the base and cap causing a slight departure from said figure.

I claim as new and desire to secure by Letters Patent:

The configuration of the body of the lamp, as hereinafter shown and described, to form a new and original design.

Therefor.
